UNITED STATES PATENT OFFICE

2,324,409

LATCH

Rollo Marple, Jackson, Mich., assignor to Hancock Manufacturing Company, Jackson, Mich., a corporation of Michigan

Continuation of application Serial No. 343,341, July 1, 1940. This application October 13, 1942, Serial No. 461,861

2 Claims. (Cl. 292—214)

The present invention relates to latches, and in particular is directed to the provision of an improved latch embodying a bolt of the rotary type. The present structure represents an improvement upon the arrangement generically claimed in applicant's copending application Serial No. 308,511, filed December 11, 1939 (now Patent No. 2,301,560 of November 10, 1942), and his application is a continuation of applicant's copending application Serial No. 343,341, filed July 1, 1940 (now abandoned).

The principal objects of the present invention are to provide an improved latch of the above indicated character, which is simple in construction, economical of manufacture, and which is positive and reliable in operation; to provide such an arrangement embodying a locking member which can be moved from a retracted to a locking position, in which latter position it positively prevents movement of the bolt in a door opening direction; to provide such an arrangement wherein a movement of the bolt occasioned by a closing of the associated door restores the locking member to the retracted position; and to provide such an arrangement wherein the locking member is operably responsive to one of the latch operating means, such as the inside handle.

With the above as well as other objects in view, which appear in the following description and in the appended claims, a preferred but illustrative embodiment of the invention is shown in the accompanying drawings throughout the several views of which corresponding reference characters are used to designate corresponding parts and in which:

Figure 1 is a fragmentary view illustrating an embodiment of the invention;

Fig. 2 is a detail view, taken along the line 2—2 of Fig. 1;

Fig. 3 is a detail view, taken along the line 3—3 of Fig. 2;

Fig. 4 is a fragmentary view corresponding generally to Fig. 3, but showing the hereinafter described locking member in the locked position thereof;

Fig. 5 is a view corresponding generally to Fig. 3, but showing the bolt in the unlocked condition;

Fig. 6 is a view, taken along the line 6—6 of Fig. 2;

Fig. 7 is a view, taken along the line 7—7 of Fig. 3;

Fig. 8 is a fragmentary view, taken along the line 8—8 of Fig. 3;

Fig. 9 is a detail view, taken along the line 9—9 of Fig. 6; and

Figs. 10 and 11, respectively, are perspective views showing certain elements of the latch in separated and relatively assembled relations.

Referring to the drawings, the present latch comprises generally a bolt 20, having a series of equiangularly spaced toothlike keeper engaging projections 20a, 20b, 20c and 20d; and a keeper, designated as a whole as 22. The bolt 20 and its associated parts are assembled within a casing having a plate-like cover 24 and an inner or base portion 26. The casing members 24 and 26 are secured together in any suitable way and are secured to the associated door 28 (Fig. 1) with the case plate members 24 and 26 lying generally parallel to the rail of the door. As will be understood, the rail may be suitably recessed or otherwise formed to receive the casing, and the casing is provided with suitable bolt openings, such as 30, to receive attaching screws or bolts. The keeper 22 is suitably secured to the door pillar 34. As most clearly appears in Figs. 3 and 6, the outer casing member 24 is interrupted in the lower portion thereof, so as to define an opening or pocket into which a tooth of the bolt 20 projects and which pocket receives the keeper 22 when the associated door 28 is in the closed position. The just-mentioned pocket is provided with a supporting abutment 36, between which and the bolt 20, the keeper 22 is wedged when the door is fully closed, so that the present construction affords both a latching and a dovetail action.

The keeper assembly 22 may, and preferably does, duplicate the arrangement described and claimed in applicant's Patent No. 2,195,179, granted March 26, 1940. As is described in more detail in the just-mentioned patent, the keeper comprises generally a retractable finger 38 and an abutment surface 40. During a closing movement of the parts, the bolt moves to the right relative to the keeper, as viewed in Fig. 3, during which movement the finger 38 is retractable by the bolt, allowing the latter to pass thereover without interference. The continued door closing movement brings the just-mentioned bolt tooth into engagement with the abutment 40, enabling the latter to rotate the bolt and bring the next successive bolt tooth into engagement with the rear face of the abutment. During an opening movement of the door, the bolt is free to rotate in a counterclockwise direction, as described below, and rolls over the abutment 40 and the finger 38 much in the relation of a gear and rack.

In the present instance, the bolt 20 is rotatably supported upon a pin 50, the respectively opposite ends whereof are secured to the casing members 24 and 26, and which pin is so positioned that in each holding position of the bolt, one tooth thereof projects into the previously mentioned pocket for cooperation with the keeper assembly 22, as described above.

The means for controlling the rotation of the bolt 20 comprises a vertically slidable wedge 52, one lower edge 53 whereof is tapered, as clearly

appears in Figs. 3, 4, 5, 10 and 11. The wedge 52 is adapted to be vertically moved between the latching position, shown in Fig. 3, and the retracted position, shown in Fig. 5, by means of the illustrative outside handle 54 and the correspondingly illustrative inside handle 56. The wedge 52 is received between the case plate members 24 and 26, and is also provided with additional guiding means comprising the guides 58 and 60. The guides 58 and 60 are secured to the member 26 and project therefrom towards the member 24.

When it occupies the latching position, the tapered face 53 of the wedge 52 lies in front of and in blocking relation to a tooth (designated 20a in Fig. 3) of the bolt 20, and is thus effective to prevent a counterclockwise or door opening rotation of such bolt. As described below, the wedge 52 is urged downwardly by a spring, and with this relation, it will be appreciated that the wedge acts to continuously urge the bolt 20 in a clockwise or door latching direction, thus affording the take-up action described in more detail in the above-identified copending application.

The housing space between the members 24 and 26 also receives a generally L-shaped retracting member 70 and a locking member 72. The locking member 72 is provided with a laterally turned flange 74 between which and the guide 58 the retracting member 70 is guided. The locking member 72 in turn extends between the previously mentioned guide 60 and an additional guide surface 76, also secured to the casing member 26, it being understood that the inner edge of the guide 58 is spaced from the inner face of the member 24 far enough to accommodate the member 72. The locking member 72 thus lies behind the wedge 52 and the retracting member 70, as viewed in Figs. 3 and 4, and directly engages and slides upon the inner face of the housing member 24. The locking member 72 has laterally offset body portions 73 and 75, which form supporting surfaces, respectively, for the wedge 52 and the retracting member 70. The portions 73 and 75 are offset approximately the thickness of the leg 55 on wedge 52, so that such leg normally lies behind the leg 118 of member 70, and such leg 118 lies above the shoulder 79 formed on wedge 52.

At the end of its leg 118, the retracting member 70 is provided with a laterally turned ear 78, which is normally received between a rollback member 80 and a biasing member 82. The rollback member 80 is provided with hub portions 84 and 86, which are rotatably journalled respectively in supplemental case plate members 88 and 90, which members are rigidly secured to and project inwardly of the door from the casing members 24 and 26. The rollback 80 is provided with a squared opening which receives the usual squared spindle 92, to which the previously mentioned outside handle 54 is connected. In order to normally bias the rollback 80 to the position shown in Fig. 6, in which position the outside handle 54 is horizontal, the member 80 is provided with a spiral spring 94, one end whereof is hooked into the body of the rollback, and the other end whereof is hooked over a stop bracket 96. The biasing lever 82 is pivotally mounted upon a pin 100, which extends between the case plate members 88 and 90, and is provided with a biasing spring 102, which continuously urges it in a counterclockwise direction, so as to enable the free end thereof to urge the member 70 downwardly. By the engagement between leg 118 of member 70 and shoulder 79 on wedge 52, the downward force on member 70 is transmitted to wedge 52.

The locking member 72 is provided with a notch having an upper surface 104 and a lower surface 106, which notch receives the end 108 of a bell-crank lever 110, which lever is pivotally supported upon a bracket 111 by a pin 112. The other end of the lever 110 is pivotally connected to a link 114, which extends to and is connected to the inside handle 56. The connection between the link 114 and the handle 56 is preferably arranged, as shown, for example, in Grund et al. Patent No. 1,760,491, so that the inside handle is normally biased to a so-called normal position in which the lever 110 occupies the position shown in Fig. 6. Suitable spring means associated with the just-mentioned connection is operative to restore the handle to the normal position after it is moved in a retracting direction. The connection is further such that if the handle is moved in a non-retracting or locking direction, it is releasably held in the locking position by a detent action.

The end 108 of the inside lever 110 also overlies a shoulder 115 formed on the retracting member 70 and member 70, in turn, is provided with an outwardly struck portion 116, which normally engages below the leg 55 of the wedge 52, which leg lies behind leg 118 of member 70, as best appears in Figs. 6, 9, 10 and 11. It will be understood, therefore, that if the inside lever 110 is rocked in a clockwise direction, as viewed in Fig. 6, such movement through the shoulder 115 elevates the retracting member 70. The latter movement, through the offset portion 116, elevates the wedge 52 from the holding position of Figs. 3 and 4 to the retracted position of Fig. 5. In the latter position, the wedge 52 does not interfere with free rotation of the bolt. The just-mentioned movement of the inside lever also elevates the locking member 72, which action is, however, without effect.

It will be understood that the wedge 52 may also be drawn upwardly to the retracted position by rotating the rollback 80 in a clockwise direction, as viewed in Fig. 6, which also elevates member 70 and, consequently, elevates wedge 52. Thus, either the inside handle 56 or the outside handle 54 may be rotated in the usual way so as to lift the wedge 52 out of holding relation to the bolt, enabling the door to be opened.

The lower end of the locking member 72 is formed as a locking member 120 and, in response to rotation of the inside lever 110 in a counterclockwise direction, as viewed in Fig. 6 (which movement results from a non-retracting movement of the inside handle 56), the locking member 72 is moved downwardly, bringing the locking portion 120 from the position shown in Fig. 3, in which it does not interfere with the rotation of the bolt, to the locking position shown in Fig. 4, in which it lies directly in the path of the bolt 20. An opening movement of the door involves a counterclockwise rotation of the bolt 20, as viewed in Fig. 4, and by blocking such rotation, the locking member 72 is operative to prevent an opening movement of the door, even though the wedge 52 should be elevated by operation of the outside handle or otherwise.

A closing movement of the door, on the other hand, produces a clockwise rotation of the bolt, as viewed in Figs. 3 and 4, during which movement the tooth, designated 20b in Figs. 3 and 4, moves upwardly. This upward movement retracts the wedge 52 and also is effective to restore the locking member 72 to the unlocked position, shown in Fig. 3.

As previously mentioned, the inside handle is

preferably arranged so that it is releasably held in either the normal or the unlocked position. If desired, and as illustrated, however, additional detent mechanism may be associated with the locking member 72. This detent mechanism comprises a spring-like member 122, which is secured to the inner face of the casing member 24 and is provided with a boss 124 adapted to enter either of a pair of openings 126 and 128 in the locking member 72. It will be understood that the boss 124 is received in the opening 126 when the locking member 72 is in the unlocked position and is received in the opening 128 when the locking member 72 is in the locked position.

Considering now the operation of the system as a whole, it will be appreciated that the parts are shown in Figs. 3 and 6 in the normal or latched condition thereof, in which the lever 82 is effective to hold the wedge 52 in its lower or holding position, thus biasing the bolt 20 in a clockwise or locking direction of rotation and enabling the tooth, designated 20c in Fig. 3, to bear against the keeper and wedge the same into engagement with the supporting dovetail surface 38.

Assuming it is desired to open the door, the outside rollback 80 may be rotated in a clockwise direction, thereby elevating the wedge 52 out of holding engagement to the bolt, as shown in Fig. 5. The same movement may be caused by rotating the inside lever 110 in a clockwise direction, in either of which events, the upward movement of the wedge 52 is resisted by the lever 82 and the spring 102. In the event the movement of the wedge is caused by the inside lever 110, the spring 94, associated with the rollback 80, retains it in the normal position shown in Fig. 6.

Upon movement of the wedge 52 to the elevated position of Fig. 5, the latch assembly and consequently the door may freely be moved to the left, as viewed in Figs. 3, 4 and 5, relative to the keeper 22, during which movement the bolt 20 rotates in a counterclockwise direction and rolls across the keeper surfaces.

The handle 54, or the handle 56, as the case may be, is released as soon as the bolt 20 passes out of cooperative relation to the keeper 22, at which time the spring 102 and the lever 82 are operative to again force the wedge 52 downwardly to the holding position shown in Fig. 3.

If the door is now moved towards the closed position, the bolt 20 initially engages the spring finger 38 of the keeper, moving it to the retracted position, and thereafter engages the leading face of the keeper abutment 40, at which time the keeper applies a rotative force to the bolt. Thus, the continued closing movement of the door rotates the bolt 20 in a clockwise direction, enabling the tooth 20b of Fig. 3 to elevate the wedge 52 toward the retracted position by an amount sufficient to let the bolt 20 rotate past the end of the wedge and bring the next successive bolt tooth into cooperative relation to the rear face of the keeper abutment 40. The latter action also enables the spring 102 to again force the wedge 52 downwardly into holding engagement with the bolt.

Assuming it is desired to render the outside handle ineffective to release the bolt, the inside handle 56 may be moved in a non-retracting direction, so as to rotate the lever 110 in a counterclockwise direction, as viewed in Fig. 6. This

movement enables the end 108 of the lever to bear against the foot 106 formed on the locking member 72 and force the latter downwardly to the previously described locking position shown in Fig. 4.

- 5 Reverse movement of the handle 56 enables the end 108 of the lever 110 to bear against the foot 106 formed on the locking member 72 and elevate the latter to the unlocked position shown in Fig. 3. Also, and as previously mentioned, a closing movement of the door, which rotates the bolt 20 in a clockwise direction enables a tooth of the bolt to bear against the lower end of the locking portion 120 and elevate the locking member 72 to the unlocked position.

What is claimed is:

1. In a latch for association between two relatively movable parts, a bolt carried by one part, said bolt having a first position in which it cooperates with an associated keeper to restrain said parts in closed position and being movable from such position so as to enable it to clear said keeper and permit an opening movement of such parts, a holding member movably carried by said one part and operatively associated with said bolt in such relation as to enable it to prevent a said movement of said bolt, an operator actuatable to retract said holding member out of cooperative relation to said bolt so as to enable a said movement of said bolt, locking means which normally occupies a retracted position out of cooperative relation to said bolt but is movable from such retracted position into a locking position in which it blocks a said movement of said bolt despite the movement of the holding member out of cooperative relation to the bolt caused by an actuation of the operator, and means operated as an incident to a closing movement of said parts for restoring said locking means to the unlocked position.
2. In a latch for association between two relatively movable parts, a bolt carried by one part, said bolt having a first position in which it cooperates with an associated keeper to restrain said parts in closed position and being movable from such position so as to enable it to clear said keeper and permit an opening movement of such parts, a holding member movably carried by said one part and operatively associated with said bolt in such relation as to enable it to prevent a said movement of said bolt, an operator actuatable to retract said holding member out of cooperative relation to said bolt so as to enable a said movement of said bolt, locking means which normally occupies a retracted position out of cooperative relation to said bolt but is movable from such retracted position into a locking position in which it blocks a said movement of said bolt despite the movement of the holding member out of cooperative relation to the bolt caused by an actuation of the operator, said bolt being movable by said keeper in a direction which is the opposite of said first mentioned bolt movement during a closing movement of said parts, and being effective during said last mentioned opposite direction of movement to restore said locking means to said retracted position thereof.
